CLAIM

The ornamental design for a lighting fixture, as shown and described.

DESCRIPTION

This application is related to commonly assigned, co-filed U.S. design patent application Ser. No. 29/791,034, filed on Dec. 27, 2021 by Molly E. McGee, entitled “Lighting Fixture”, and commonly assigned, co-filed U.S. design patent application Ser. No. 29/791,035, filed on Dec. 27, 2021 by Molly E. McGee, entitled “Lighting Fixture”, which applications are incorporated herein by reference in their entireties.

FIG. 1 is a front right perspective view from below of a lighting fixture according to the new design;

FIG. 2 is a rear left perspective view from above thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top view thereof;

FIG. 8 is a bottom view thereof;

FIG. 9 is a front left perspective view thereof, but shown in a rotated configuration;

FIG. 10 is a front right perspective view from below thereof, but shown illuminated;

FIG. 11 is a rear left perspective view from above thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top view thereof;

FIG. 17 is a bottom view thereof; and,

FIG. 18 is a front left perspective view thereof, but shown in a rotated configuration.

The broken lines in the drawings illustrate portions of the lighting fixture that form no part of the claimed design.

The stippling shown in FIGS. 10-13 and 18 is solely for the purpose of illustrating the appearance of illumination and does not represent texture or surface ornamentation.

(Continued)

The lighting fixture is shown with symbolic breaks. The appearance of any portion of the article between the break lines forms no part of the claimed design.
